Patented Sept. 26, 1967

208,696

MOBILE FLOWER SHOP

George A. Rupp, Jr., 1919 Columbus Ave.,
Bay City, Mich. 48706

Filed Nov. 2, 1966, Ser. No. 4,524

Term of patent 14 years

(Cl. D14—3)

Fig. 2

Fig. 1

FIG. 5

FIG. 1

FIG. 3

FIG. 1 is a side elevational view of my mobile flower shop, the vehicle wheels, hood, bumper, and ground line being shown in broken lines.

FIG. 2 is a top plan view thereof, vehicle wheels, hood, bumper and ground line being shown in broken lines.

FIG. 3 is a front elevational view, the vehicle wheels, hood, and ground line being shown in broken lines.

FIG. 4 is a rear elevational view, the vehicle wheels and the ground line being shown in broken lines.

FIG. 5 is an opposite side elevational view, the vehicle wheels, hood, bumper and ground line being shown in broken lines.

The dominant features of my design reside in the portions shown in full lines.

I claim:

The ornamental design for a mobile flower shop, substantially as shown and described.
